UNITED STATES PATENT OFFICE

156,066

DESIGN FOR A COIN BANK

William J. Ayers, New Castle, Pa.

Application March 24, 1948, Serial No. 145,315

Term of patent 14 years

(Cl. D34—11)

To all whom it may concern:

Be it known that I, William J. Ayers, a citizen of the United States, residing at New Castle, in the county of Lawrence and State of Pennsylvania, have invented a new, original, and ornamental Design for Coin Bank, of which the following is a specification, reference being had to the accompanying drawing, forming part thereof.

Figure 1 is a front view of a coin bank, showing my new design;

Figure 2 is a back view of the same, and

Figure 3 is a side view of the same.

I claim:

The ornamental design for a coin bank, as shown.

WILLIAM J. AYERS.
